UNITED STATES PATENT OFFICE.

CHARLES W. PARK, OF NEW YORK, N. Y.

DESIGN FOR A MEDALLION.

SPECIFICATION forming part of Design No. 35,883, dated April 29, 1902.

Application filed February 11, 1902. Serial No. 93,636. Term of patent 7 years.

To all whom it may concern:

Be it known that I, CHARLES W. PARK, a citizen of the United States, and a resident of the city of New York, borough of Manhattan, in the county and State of New York, have invented and produced a new and original Design for a Medallion, of which the following is a specification, reference being had to the accompanying drawing, forming a part thereof, which represents a perspective view of a medallion embodying the features of my design.

The leading features of the design consist in the opposing decorative figures appearing on the face of the medallion near the top and near the bottom, each of which figures comprise a curved base-line terminating in oppositely curved C-scrolls and a central V-scroll, at the fork of which a trefoil figure is seen. The terminals of the branches of the

V-scroll appear with openings, while a third opening is visible at the junction of the members of the said V-scroll.

Minor features of the design consist in the representation of a conventional full-rigged ship and in the shape of the medallion, which is oval in general outline and its side faces are convexed.

Having thus described my invention, I claim as new and desire to secure by Letters Patent—

The design for a medallion herein shown and described.

In testimony whereof I have signed my name to this specification in the presence of 35 two subscribing witnesses.

CHARLES W. PARK.
